UNITED STATES PATENT OFFICE.

HERMAN HOFF, OF CHICAGO, ILLINOIS.

ACID-CHAMBER FOR GAS-GENERATORS.

SPECIFICATION forming part of Letters Patent No. 365,254, dated June 21, 1887.

Application filed January 15, 1887. Serial No. 224,394. (No model.)

To all whom it may concern:

Be it known that I, HERMAN HOFF, a citizen of the United States, and a resident of Chicago, county of Cook, and State of Illinois, have invented new and useful Improvements in Acid-Chambers for Gas-Generators, of which the following is a specification, reference being had to the accompanying drawings, illustrating the invention, in which—

10 Figure 1 is a vertical sectional elevation of my improved acid-chamber; Fig. 2, a horizontal section thereof on line *x*, Fig. 1.

This invention relates to an improvement in acid-chambers to be used in connection 15 with an alkaline-chamber for generating carbonic-acid gas in the manufacture of soda-water; and the particular improvement consists of a siphon-pipe in connection with a plunger-valve, the advantage of which is a 20 simplification and compactness of the parts and greater certainty of action.

In the operation of an apparatus for charging water with carbonic-acid gas it is necessary to have at a certain time a free circulation 25 of the gas through both the acid and alkaline or marble-dust chambers and then to drain the acid-chamber that the chemicals may be neutralized. This has been before accomplished by a stationary siphon placed 30 either outside or inside of the acid-chamber. My internal siphon is, however, a material improvement over those formerly employed, not only as to the advantages mentioned, but in the simplicity of its operation and durability.

35 A I represent the shell of the acid-chamber Q, which is made of cast-iron and lined with lead, *a*, or other non-corrosive metal.

R T represent the pipe which is to connect with an alkaline-chamber in the same manner that the two chambers are now connected 40 by a like pipe. This pipe is also lined at *r* by non-corrosive metal, which is enlarged at E to form a seat for the plunger-valve B. This valve is made of non-corrosive metal and has 45 formed in it a passage, C, which when the valve is on its seat E, communicates with the pipe R T, the two passages C and R T forming the longer pipe of the siphon, the shorter pipe of which is shown at D. The upper end 50 of the plunger B connects with a stem, J, which is supported by ordinary mechanism,

L M, the upper end of the stem being provided with a screw-thread, N, whereby a lever nut, K, may be turned to shut or unseat the valve B.

H represents the ordinary acid-supply pipe, and W the pipe which is to be connected with an ordinary pipe leading to the alkaline-chamber below.

S represents a check-valve, employed simply 60 to stop the flow of acid from chamber A in case the valve B should not shut tight on its seat, or when the communication of the two chambers is to be suspended and the valve B left open.

The operation is as follows: The valves B G are to be shut, as shown, and the valve S opened and the fluid acid put in the chamber Q. The valve G is then to be opened and the valve B to be raised by the lever nut K, allowing 70 the acid to enter the alkaline-chamber below and the pressure in the two chambers to equalize. The valves G B are then to be shut and the contents of the alkaline-chamber to be drawn off till it has two or three pounds 75 less pressure than the acid-chamber. The valve or cock G is then to be opened. This will set the siphon C D to work till the contents of the chamber Q are drawn off into the chamber below and the chemicals neutralized. 80 It is proper to state that the pipe W, which is to have a tight connection with the alkaline-chamber below, is simply to obtain a quicker equalization before the siphon is put to work. Therefore nothing new is claimed for it. 85

I claim as new and desire to secure by Letters Patent of the United States—

In acid-chambers for gas-generators, the vertical reciprocating valve B, placed therein and having a vertical pipe, C, formed within 90 its lower portion, and the pipe D, connecting with the upper end of pipe C, to form a siphon, and the stem part J of the valve, provided with a screw-thread, N, passing through a nut at the top portion of the case attachment L M, 95 in combination with the lever-nut K, for operating the valve the same as specified.

HERMAN HOFF.
